UNITED STATES PATENT OFFICE

HOWARD O. STOUT, OF BLACKWELL, OKLAHOMA

AUTOMATIC SHUT-OFF GAS VALVE

Application filed February 2, 1932. Serial No. 590,495.

This invention relates to shut-off valves and more particularly to an automatic shut-off valve which is adapted to be interposed in a gas line.

5 An object of this invention is to provide an automatic valve construction of this kind which is actuated by atmospheric pressure operating on a flexible diaphragm to close the valve upon drop in the pressure in the 10 gas line below a predetermined degree.

Another object of this invention is to provide an automatic valve of this kind which is so constructed as to prevent the opening of the valve until the gas pressure has 15 returned to normal or to a predetermined degree.

The above and various other objects and advantages of this invention will in part be described in and in part be understood 20 from the following detailed description of the present preferred embodiment, the same being illustrated in the accompanying drawing wherein there is disclosed a longitudinal section taken substantially through the 25 longitudinal center of a device constructed according to the preferred embodiment of this invention.

Referring to the drawing wherein like numerals of reference designate corresponding parts throughout the several views, the 30 numeral 16 designates a lower portion of a diaphragm casing and the numeral 16' designates an upper or complementary portion of the diaphragm casing or housing, these 35 complementary portions 16 and 16' being secured together by means of securing elements in the form of bolts or threaded members 20.

40 A valve housing 17 is secured to the lower casing member 16 and is provided with an intake port 12 and an outlet port 13. This valve housing 17 is also provided with a port 10 communicating with the pressure chamber of the diaphragm housing, this 45 pressure chamber being disposed below a diaphragm 1 secured between the upper and lower housing member 16' and 16, respectively. This diaphragm 1 is of flexible construction and is provided with a centrally 50 disposed stem 2 which extends downwardly

through an opening 18 provided in the lower casing 16 and in the valve housing 17, and the lower end of this stem 2 projects into the interior of the valve housing 17.

55 A valve head or member 4 is secured to a rock lever 3 mounted on a pivot 5 and is adapted to engage a valve seat 8 to close the outlet or discharge port 13. This rock lever or valve operating member 3 has the free end thereof or the end oppositely from the 60 valve head 4 disposed in the path of the stem 2 and the upward swinging movement of this lever 3 is controlled by an adjustable stop member 9 threadably mounted in the 65 housing 17.

70 The valve lever 3 has attached thereto a pair of springs 6 and 7, one end of these springs being attached to the lever 3 and the opposite ends being attached to the housing 17, the point of attachment of the springs 6 and 7 to the housing 17 being slightly 75 above the pivot 5 so that when the lever 3 is swung into a position to hold the valve head 4 in open position, these springs 6 and 7 will constantly maintain the valve head in 80 open position, being disposed above the axis of the pivot 5. However, when the lever operating stem 2 moves downwardly and strikes the lever 3 so as to swing this lever into closed position, the force of the stem 2 85 will swing this lever downwardly until the springs 6 and 7 pass below the pivot 5 whereupon the tension of the springs 6 and 7 will automatically swing the lever 3 so as to carry the head 4 into contact with the valve seat 8 and thereby close the discharge port. The upper diaphragm casing member 16' is 90 provided with a port 11 communicating with the atmosphere so that the atmospheric pressure will operate on the upper surface 95 of the diaphragm 1.

A cam member 14 is pivotally mounted as at 19 to the housing 17 and this pivot 19 is extended outwardly of the housing and provided with an operating means for rocking the cam member 14 in an upward direction for contact with the lever 3 so as to swing this lever 3 into open position against the action of the springs 6 and 7. The free end of this cam member 14 has 100

secured thereto a spring 15, the opposite end of the spring 15 being attached to the housing 17 so as to constantly urge this cam member 14 into inoperative position and out of engagement with the lever 3.

In the operation of this device, the intake port 12 is connected to a source of gas supply under pressure and the port 13 may be connected to a gas appliance. The weight 10 of the stem with its attaching means for attaching the stem to the diaphragm 1 is such that the normal pressure of the gas entering the housing 17 will maintain this stem in its uppermost or inoperative position 15 against the atmospheric pressure entering through the port 11. In this position, the lever 3 may be maintained in a substantially horizontal position by the springs 6 and 7 which will be disposed above the axis of the 20 pivot 15. In this position also the free end of the lever 3 contacts with the stop member 9.

When the gas pressure in the interior of the housing 17 falls below a predetermined 25 degree, the diaphragm 1 will drop downwardly under the weight of the stem 2 and under the action of the atmospheric pressure on the upper surface of the diaphragm 1. The lower end of the stem 2 will strike the 30 free end of the lever 3 and force this lever to rock out of the horizontal position and after the springs 6 and 7 have passed below the pivot 3, the tension thereof will automatically swing the head 4 into contact with 35 the valve seat 8 and thereby close the discharge port 13. This valve 4 will be maintained in closed position until the cam member 14 has been swung so as to engage the lever 3 and swing this lever 3 into a horizontal position.

In the event the gas pressure has not returned to normal, the valve will be returned to its closed position under the gravitating action of the lever operating member 2 and 45 in this manner the valve cannot be accidentally opened until the gas pressure has returned to normal. The stop member 9 can be appropriately adjusted so that only a slight pressure or movement of the lever operating member 2 will effect swinging 50 of this lever into open position. The diaphragm 1 may be constructed of any desired material and is preferably made of material which is very flexible but which 55 is impervious to the action of the gas within the housing 17.

It is, of course, understood that various changes and modifications may be made in the details of construction and design of 60 the above specifically described embodiment of this invention without departing from the spirit thereof, such changes and modifications being restricted only by the scope of the following claims.

65 What is claimed is:—

1. An automatically operated valve as set forth comprising a housing having an intake and an outlet port, a valve for closing one of said ports, a valve seat for said valve, a rock lever connected at one end to said valve, 70 means engaging the lever intermediate its ends for rockably mounting the lever in the housing, means engaging the opposite end of the lever to limit the swinging movement thereof into open position, gravity actuated pressure controlled means engaging said opposite end of the lever to partially swing the lever into closed position, and yieldable means engaging the housing and the lever to swing the lever into completely closed 80 position.

2. An automatically operated valve as set forth comprising a housing having an intake and an outlet port, a valve for one of said ports, a valve seat for said valve, a rock lever connected at one end to said valve, 85 means engaging the lever intermediate its ends to rockably mount the lever in the housing, adjustable stop means carried by the housing and engaging the opposite end of the lever to limit the swinging movement thereof into open position, a diaphragm supported by the housing, means carried by the diaphragm and engaging the opposite end of the lever to partially swing the lever into closed position, and yieldable means engaging the lever and the housing to completely swing the lever into closed position.

3. An automatically operated valve as set forth comprising a housing having an intake and an outlet port, a valve for closing one of the ports, a valve seat for the valve, a rock lever secured at one end to said valve, means for rockably mounting the lever in the housing, stop means carried by the housing and engaging the opposite end of the lever to limit the swinging thereof into open position, a diaphragm supported by the housing, a lever engaging member carried by the diaphragm and projecting into the housing in the path of the opposite end of the lever to swing the lever into partially closed position upon decrease in the pressure within the housing, springs engaging the housing and the opposite end of the lever to completely swing the lever into closed position, and manually operable means carried by the housing and having a portion thereof projecting outwardly of the housing to manually swing the lever into open position.

4. An automatically operated valve comprising a valve housing having an intake and an outlet port, a valve for closing one of the ports, a valve seat for said valve, a rock lever connected at one end to the valve, means engaging the lever intermediate its ends to rockably mount the lever in the housing, stop means engaging the opposite end of the lever to limit the swinging movement thereof into open position, a dia- 130

phragm housing secured to said first housing, a diaphragm within the housing, said first housing and said diaphragm housing having a connecting port to permit the pressure in the first housing to flex the diaphragm, a lever operating member carried by the diaphragm and engaging one end of the lever to partially swing the lever into partly closed position, yieldable means engaging the lever to completely swing the lever into closed position, and manually operable means having a portion thereof disposed within the housing and a portion without the housing to manually swing the valve into opened position.

In testimony whereof I hereunto affix my signature.

HOWARD O. STOUT.
